UNITED STATES PATENT OFFICE

ALFRED SCHMIEDER, OF MASPETH, NEW YORK

SCREW CLAMP

Application filed November 21, 1929. Serial No. 403,692.

My invention relates to improvements in means for clamping parts in position to facilitate the securement or working thereof, such as in the art of woodworking, and the same has for its object to provide a simple, efficient and reliable device which is readily manipulated and secured in position to exert a clamping action along a plurality of lines of direction, or at a plurality of points.

Another object of the invention is to provide a device of the character specified in which certain of the clamping components thereof are capable of being relatively moved to exert conjointly a third clamping action along a line of direction extending transversely relative to the lines of direction of said clamping components.

Another object of the invention is to provide a device of the character specified in which an attachment may be readily connected to a pair of ordinary clamps for causing positive movement thereof towards each other to exert a clamping action along a line of direction extending transversely relative to the lines of direction of the individual clamps.

Another object of the invention is to provide a device of the character specified which includes an auxiliary clamping component capable of being readily attached to the device in various positions as required for exerting a supplemental or fourth clamping action.

Other objects will in part be obvious and in part be pointed out hereinafter.

In the accompanying drawing:

Figure 1 is a plan of one form of device constructed according to and embodying my said invention;

Fig. 2 is an elevation thereof;

Fig. 3 is a view showing a modified form of supplemental clamping component; and

Fig. 4 is a detail view partly in section.

Referring to the drawing the clamping means includes a pair of ordinary clamps 10 and 12, each comprising a standard 14 having a lower arm 16 secured thereon and upper arm 18 slidable thereon. The outer end of lower arm 16 is provided with a universally swiveled abutment member 20 adapted to engage a piece or member to be

clamped and the outer end of the upper arm 18 is provided with a screw 22 threaded therethrough and having a universally swiveled abutment 24 cooperating with the abutment 20. The two clamps 10 and 12 are substantially alike in construction.

The clamps 10 and 12 are connected together by means 26 for moving the clamps towards each other to conjointly exert a clamping action along a transverse line. The connecting means 26 includes a pair of arms 28 and 30 preferably provided with hook-like or slotted end portions 32 and 34 adapted to embrace the standards 14 to extend laterally towards each other and secured to the standards by the set screws 36. The means 26 may be adjusted along and secured to the standards at various points relative to the work so that the work does not interfere with the operation of the device. The member 30 is pivoted at 38 intermediate the ends thereof to the member 28 near the outer end of the latter, and extends transversely of the member 28 and rearwardly beyond the same. The outer end of the arm or member 30 carries a nut 40 swiveled on the pivot 42. A clamping screw 44 passing through and cooperating with the nut 40 is connected at the outer end 46 thereof to the arm 28 contiguous to the inner end thereof, said end 46 being rotatably retained in the swiveled member 48 pivoted at 50 on arm 28.

Supplementary or auxiliary clamping is also obtained by a clamping component 52 constituting an attachment which may be secured to either standard 14 by means of the nut 54 having a slot 56 adapted to engage the standard 14, and secured thereto by a screw 58. A clamping screw 60 passes through the nut 54 and is provided with a universally movable abutment 62 at the outer end thereof. The clamping means 52 provides the fourth clamping component and exerts a clamping action along a line extending transversely of the lines of clamping action of the other three clamping components.

As shown at Fig. 3 the fourth clamping component 52a may include a nut portion 64 having a standard engaging slot 56a extending

ing parallel with the threaded opening 66 and a standard engaging slot 68 extending at an angle to the opening 66. By securing the means 52^a to either standard 14 through slot 68, the clamping action is exerted at an inclination relative to the work. By securing the means 52^a to the standard through slot 56^a the clamping action is exerted normally relative to the work.

In operation, the actuating means 26 are readily secured to the clamping components 10 and 12 by engaging the slotted portions 32 and 34 with the standards 14 and securing the same by set screws 36. The clamping components 10 and 12 are then engaged with the work, such as, for example, the pieces or members A and B, by adjustment of the screws 22. By rotating the screw 44 the clamping components 10 and 12 move towards each other to exert a third clamping action along a transverse line and cause the pieces or members A and B to be firmly pressed into engagement with each other at the contiguous edges C thereof.

In my invention the clamping components 10 and 12 therefore form conjointly a third clamping component, thereby rendering the device more universal and flexible and enlarging the usefulness thereof. When required, such as for example when a third piece or member D is to be joined or otherwise worked in contact with the pieces A and B, the fourth clamping component 52 or 52^a may be secured in position on either standard 14 and the screw 44 thereof adjusted to clamp the member or piece D to retain the same in engagement with the pieces A and B. When it is necessary to operate the fourth clamping component at an angle, for example, as shown at Fig. 3, as when an angular piece E is employed, the component 52^a is employed and secured to the standard 14 through inclined slot 68.

My device may be readily manipulated and secured in position, and provides three or four different clampings as required. The working or securement of the pieces is thereby greatly facilitated and the device may be employed in connection with types of work for which the individual clamps 10 or 12 are inadequate, thereby providing a device having an enlarged range of usefulness, and particularly in connection with the fabrication of veneered articles or in connection with working upon curved surfaces.

Having thus described my invention what I claim and desire to secure by Letters Patent is:

1. A device of the character described comprising a plurality of clamps, each including a standard, arms projecting from said standard and slidable thereon relative to each other, and relative adjustable clamping members carried by the outer end of said arms, and a pivotal connection between

said standards intermediate said arms for allowing the swinging of said clamps towards each other to exert a transverse clamping action, and actuating means for swinging the clamps about the pivotal connection.

2. A device of the character described comprising a plurality of clamps, each including a standard and clamping arms relatively slidable thereon, and means engaging said standards for sliding adjustment longitudinally thereof and providing a pivotal connection between said clamps for allowing movement thereof towards each other to exert a transverse clamping action.

3. A device of the character described comprising a plurality of clamps, each including relatively adjustable clamping members adapted to exert a clamping action along a certain line of direction, a pivotal connection between said clamps, and a screw carried by said connection and connected with relatively movable parts thereof for swinging said clamps to exert a transverse clamping action, said screw being connected to said parts to extend forwardly between said clamps at an angle to the direction of the transverse clamping action.

4. A device of the character described comprising a plurality of clamps including standards and clamping members thereon adjustable relative to each other, and means connected to said standards and including relative movable parts providing a pivotal connection between said clamps for swinging the same towards each other to exert a transverse clamping action, swiveled members on said parts one in advance of the other on a line intermediate said standards and a screw cooperating with said swiveled members for actuating said clamps.

5. A device of the character described comprising a pair of clamps, each including a standard and relatively adjustable clamping members thereon for exerting a clamping action in a certain line of direction, and means connecting said clamps for allowing movement thereof towards each other to exert a transverse clamping action, and including portions engaging said standards for sliding adjustment longitudinally thereof and a pivotal portion intermediate said first named portions, and actuating means carried by said connecting means and cooperating with the relative movable parts thereof.

6. A device of the character described comprising a pair of clamps, each including a standard, arms projecting from said standard and slidable relative to each other longitudinally of the standard, and relatively adjustable clamping members at the outer ends of said arms, and a pivotal connection between said clamps including portions engaging said standards for sliding adjustment

longitudinally thereof, and a screw carried by said connection and cooperating with the relatively movable parts thereof for moving said clamps to exert a transverse clamping action.

5 7. A device of the character described comprising a pair of clamps including standards, arms connected to said standards and extending towards each other, one of said arms being pivoted centrally thereof to the other arm contiguous to the free end thereof and extending rearwardly relative thereto, swiveled members carried by said arms, and a clamping screw coacting with said swiveled members for controlling the angular relation of said arms, and serving to move said clamps toward each other to exert a clamping action.

8. A device of the character described comprising a pair of members having slotted portions at the outer ends thereof for detachably engaging the standards of a pair of clamps, one of said members being pivoted centrally thereof to the inner end of the other member and extending rearwardly thereof, a swiveled nut on the inner end of the centrally pivoted member, a clamping screw coacting therewith, and a swiveled member on said other member adjacent the outer end thereof and rotatably retaining said screw connected thereto.

9. A device of the character described comprising an auxiliary clamping means for a clamp including a nut having a threaded opening therein and slots disposed at opposite sides of said opening and adapted to engage the standard of said clamp, one of said slots being disposed in parallelism with the axis of said opening and the other of said slots being disposed at an inclination thereto, means for securing the nut to the standard, and a clamping screw extending through the opening.

10. A device of the character described comprising an attachment for moving clamps towards each other to exert a third clamping action including slotted portions at the outer ends thereof adapted to engage the standards of the clamps for sliding adjustment longitudinally thereof, a pivotal connection between the slotted portions having the pivot thereof disposed parallel to the direction of sliding adjustment of the attachment, and a screw carried entirely by the attachment and coacting with the relatively movable parts thereof for effecting said movement.

11. A device of the character described comprising an attachment for swinging clamps towards each other to exert a third clamping action including slotted portions at the outer ends thereof adapted to engage the standards of the clamps for sliding longitudinal adjustment thereon, and arms extending inwardly therefrom and pivoted together on an axis disposed parallel to the direction

of sliding adjustment, and a screw carried by the attachment and coacting with the relatively movable parts thereof for effecting said swinging movement.

12. A device of the character described, a pair of clamps, each including a standard, a fixed arm, a sliding arm, and relatively adjustable clamping members at the outer ends of the arms, and an attachment for moving the clamps towards each other to exert a transverse clamping action including slotted portions engaging the standards for sliding adjustment thereon between said arms, and a connection between said slotted portions allowing relative movement thereof, and including a screw carried by the attachment and coacting with the relatively movable parts thereof for effecting the movement thereof.

In testimony whereof, I have signed my name hereto.

ALFRED SCHMIEDER.
